UNITED STATES PATENT OFFICE.

REAMER H. DYER, OF ROANOKE, VIRGINIA.

WASTE RETAINER.

Application filed July 25, 1927. Serial No. 208,903.

This invention relates to waste retainers for car axle boxes, and is in the nature of an improvement to, or modification of, the waste retainer disclosed and claimed in my prior application, Ser. No. 125,363, filed July 28, 1926.

The device of said application is a single piece of metal, preferably pressed steel, comprising a transverse member adapted to extend across the face of the journal collar, and legs or side members extending back on each side of the journal, the outer edges of each of said members having a downwardly extending flange to engage and retain the waste, while from the inner edges of said side members extend upwardly cheek members bent over at their tops to form horizontal bearing surfaces adapted to be engaged by the bottom faces of the journal brass, whereby the retainer is kept in its proper position.

The device, constituting the present invention, is similar to the said prior device, but is equipped with additional means for engaging the waste. This means consists, first, in serrations or teeth formed on the lower edges of the flanges, or some of them, and, secondly, in additional serrated flanges projecting downwardly from the inner edges of the side members parallel to the flanges on the outer edges of said members.

This device is illustrated in the accompanying drawing, in which Fig. 1 is a longitudinal vertical section of a car axle journal box equipped with the new waste retainer;

Fig. 2 is a sectional end view taken on line 2—2 of Fig. 1;

Fig. 3 is a plan view of the waste retainer, and

Fig. 4 is a cross section of the same on line 4—4 of Fig. 3.

In these views, the front transverse member 1 of the retainer has a downwardly projecting flange 2 on its front edge and a shorter downwardly projecting flange 3 on its rear edge, the bottom edge of the flange 3 being serrated or provided with teeth 4. The front flange 2 might also be serrated but I prefer to leave it smooth to facilitate the handling of the device.

The legs or side members 6 are cut out on their inner sides adjacent the transverse member 1, as shown at 7, to accommodate the collar 8 of the axle journal 9, and are recessed on their outer sides, as shown at 10, to accommodate ribs, not shown, on the inner

walls of the box. The box 11, shown in the drawing, is a cast iron box which does not have such ribs, which are present, however, in pressed steel boxes, and I prefer to make my waste retainer so that it can be used in any form of box.

The rear ends 12 of the legs 6, beyond the recesses 10, are of less width than the front portions of said legs, which is also for the purpose of permitting the ready insertion and removal of the device from boxes having the internal ribs.

The outer edges of the front and rear portions of the legs are bent downwardly to form flanges 13 and 14, respectively, the flanges 14 on the rear portions 12 being of less depth than the flanges 13 on the front portions, and both flanges have their bottom edges serrated or provided with the teeth 15, for the purpose stated. From the inner edges of the central portions of the side members 6 project upwardly the cheek members 16, the tops of which are bent over outwardly to form horizontal bearing surfaces 17, which engage the bottom faces of the journal brass 18 and are kept in contact therewith by the pressure of the compressed waste.

As far as described above, the device is an integral structure, preferably of pressed steel, and differs from my prior device merely in the provision of the teeth on the flanges. But the present device comprises further means to engage the waste, which means consists in an angle strip 21 secured to each side member 6. The horizontal leg of each strip is riveted, as shown at 20, to the underside of the corresponding side member, and the vertical leg of each strip projects downwardly from the inner edge of said member parallel to the flanges 13 and 14 on the outer edges of the same. The bottom edges of the strips 21 are serrated, as shown at 22. By this construction, the retainer has a more positive engagement with the waste to further prevent its tendency to creep up on the side of the journal opposite to the direction of movement of the vehicle or to become otherwise displaced.

Having thus described my invention, what I claim is:

1. A waste retainer for car axle journal boxes, comprising a U-shaped metal structure the end and side members of which have downwardly projecting flanges with teeth on their lower edges to engage the waste, and

upwardly projecting means on said side members to engage the bottom surfaces of the journal brass.

2. A waste retainer for car axle journal boxes, comprising a U-shaped metal structure adapted to straddle the axle journal in the journal box, the front transverse and side leg members of said structure being provided with downwardly projecting flanges 10 on both their inner and outer edges, and means on the side leg members to engage the journal brass.

3. A waste retainer for car axle journal boxes, comprising a U-shaped metal structure adapted to straddle the axle journal in the journal box with its transverse member passing across the end face of the journal collar and having downwardly projecting flanges on its inner and outer edges, and with 20 its side members adapted to lie along the

sides of the journal and having downwardly projecting flanges on their inner and outer edges, said last mentioned flanges being serrated or toothed on their lower edges, and means projecting upwardly from said side 25 members to engage the bottom surfaces of the journal brass.

4. A floating waste retainer for car axle journal boxes, comprising a flanged transverse member adapted to lie across the end 30 of the journal, side members adapted to lie one on each side of the journal, parallel serrated flanges on each of said side members, and cheek members rising from the inner edges of said side members and adapted to 35 engage the journal brass.

In testimony whereof I have hereunto set my hand.

REAMEY H. DYER.
